UNITED STATES PATENT OFFICE.

JOHN A. SCHLEICHER, OF SAGINAW, MICHIGAN, ASSIGNOR TO LUFKIN RULE CO., OF SAGINAW, MICHIGAN, A CORPORATION OF MICHIGAN.

DESIGN FOR A BASE FOR A MICROMETER HEIGHT GAUGE.

Application filed March 18, 1925. Serial No. 12,759. Term of patent 14 years.

To all whom it may concern:

Be it known that I, JOHN A. SCHLEICHER, a citizen of the United States, residing at Saginaw, in the county of Saginaw, State of Michigan, have invented a new, original, and ornamental Design for Base for Micrometer Height Gauge, of which the following is a specification, reference being had to the accompanying drawing, forming part thereof.

Fig. 1 is a perspective view of the article showing my new design.

Fig. 2 is a side view.

Fig. 3 is a front view.

I claim—

The ornamental design for a base for a micrometer height gauge as shown.

JOHN A. SCHLEICHER.
